**TEST AND RESET CIRCUIT FOR INTRUSION
ALARM SYSTEM**

Raymond D. Lucas and George C. Byrne, Mountain View, and John C. McDonald, Los Altos, Calif., assignors to Sylvania Electric Products Inc., a corporation of Delaware

Filed Dec. 18, 1961, Ser. No. 160,116
8 Claims. (Cl. 340—214)

This invention relates to intrusion alarm systems, and more particularly to a reset and test circuit which enables such a system to be returned to its readiness or reset state after it has been alarmed and which provides a system operativeness check by artificially simulating an unauthorized intrusion.

Intrusion alarm systems of the type described in Patent Number 2,660,718 protect a specific area by beaming microwave energy into the area and by processing signals from the area in a microwave receiver so as to sound or otherwise indicate an alarm when an intruder is present. Such systems usually are monitored at a central station which is remote from the protected area. When an alarm is sounded and after its cause has been investigated at the protected area, the guard should be able promptly to reset the system, i.e., return it to its readiness state. In order to permit the guard to reset the receiver and leave the protected area without alarming the system, a relatively long delay (i.e., 1 minute) should be provided between the time the guard initiates the reset operation and the time the system is again in its readiness state.

Allied to this resetting function is a built-in circuit capable of testing itself to determine if its components, connections and networks are operating properly. This is done by deliberately injecting into the circuit a signal similar to that produced by an intruder. If the system is functioning properly, the alarm is sounded automatically. The test circuit should then promptly turn off the alarm and return the system to its readiness state. For this purpose, a short time delay (10 seconds) is desirable.

A general object of this invention is the provision of a test and reset circuit which incorporates the above features.

This and other objects of the invention will become apparent from the following description of a preferred embodiment thereof reference being had to the accompanying drawing showing an intrusion alarm system with a block and circuit diagram of the test and reset circuit.

Referring to the drawing, the area A to be protected lies between antennas 1 and 2, connected respectively to a continuous wave radio frequency transmitter 3 and a receiver 4. Movement of an object in area A produces a Doppler shift in the frequency of the received waves which appears in the output of the receiver on lines 5, 5' and is detected in discriminating circuits 6, 6'. Two circuits 6 and 6' are provided for improving reliability through redundancy and it is the function of each to discriminate between suprious and intruder signals on the basis of the Doppler frequency shift, the magnitude of the signal and the persistence (time integral) of the signal. The discriminator circuits 6 and 6' may be of the type described in copending application on "Signal Processing Circuit For Intrusion Alarm System," by John C. McDonald, Serial No. 200,019, filed May 31, 1962, and assigned to the assignee of this application or the types described and referenced in "Coincidence Techniques for Radar Receivers Employing a Double Threshold Method of Detection," by E. Endresen and R. Hedemark, page 1561, volume 49, Proceedings of the IRE, No. 10, October 1961.

The outputs of discriminating circuits 6 and 6' on lines 7, 7' pass to an OR gate 10 which responds to the output of either to cause an alarm relay 11 to actuate an alarm mechanism 12 such as a bell or light. Relay 11 preferably is normally energized, and produces an output to activate alarm 12 when the relay is de-energized.

Receiver 4 also produces a direct current output on line 14 in response to reception of the continuous wave by antenna 2, and this D.C. component is applied to the OR gate 10 which keeps relay 11 energized. If this D.C. output of the receiver falls below a certain level, which is indicative of malfunctioning of any of the components from the transmitter 1 to receive 4, the alarm is given.

15 In order to test operability of the intrusion alarm system described above, a test circuit is provided by which a signal representing an intruder is deliberately injected in the system. If alarm 12 is actuated, as it should be, the test circuit should then reset the entire system automatically in a relatively short time, say 10 seconds.

10 The test circuit comprises a signal generator 20 having a push button 21 by which the guard or operator initiates the test cycle. This generator may comprise a blocking oscillator capable of producing a pulse on output lines

25 22 and 23 when push button 21 is depressed, and a source of unidirectional potential which normally produces on a third output line 25 a positive voltage which is changed to a negative voltage when push button 21 is depressed.

30 The pulse on line 22 is applied to receiver 4 and is of such character that it appears as an intruder signal so as to cause alarm device 12 to function if all of the intervening circuits are operating properly, or conversely, to indicate a malfunction if the alarm does not respond. If either of the redundant discriminator circuits 6 or 6' is faulty, the alarm is given but the system will not reset. This indicates that one of the circuits 6 or 6' is defective. The circuits by which this is accomplished are explained more fully below.

40 Output line 23 of the test generator is connected to a triple input AND gate 26 as are output lines 27 and 27' from discriminator units 6 and 6', respectively. As the output of gate 26 initiates the system reset cycle both discriminator circuits must be operating properly in order that resetting take place. Gate 26 is connected by line

45 28 to a bi-stable multivibrator or flip-flop 30 which is actuated (set) in response to an output from the gate. A push button 31 preferably located at or near protected area A and electrically connected to flip-flop circuit 30 as indicated by broken line 32 also actuates the flip-flop when depressed.

50 Flip-flop circuit 30 is connected by line 33 to a time delay network 35 the output of which appears at line 36 and is applied to a trigger amplifier 37. This delay network, described below, produces a long delay (approximately 1 minute) for signals applied to it by actuation of push button 31, and a short delay (approximately 10 seconds) for signals produced by depressing button 21 on generator 20. Trigger amplifier 37 is connected by

60 line 38 to a normally open reset relay 39 and produces an output of sufficient amplitude to operate the latter. Relay 39 may comprise a coil 40 and contacts 41 and 42 which, when closed, connect a source of energy 43 to relay outputs 44 and 45. As long as there is an input on line 36 to amplifier 37, the latter continues to conduct and relay 39 operates to close its contacts. When the input to amplifier 37 is removed, its output on line 38 drops and relay 39 opens.

65 Delay network 35 comprises a normally conducting gate transistor 50 connected in parallel with an amplifier transistor 51, and a delay control transistor 52. Amplifier transistor 51 is normally non-conducting and has a

capacitor 53 connected between its base 55 and collector 56, a bias resistor 60 connected between base 55 and ground, emitter bias resistor 61 connecting emitter 57 to ground, and load resistor 62 connected between collector 56 and the negative supply voltage designated $-V$. Transistor 51, capacitor 53, and resistors 60 and 61 are connected to function as a Miller integrator circuit as described in Waveforms, volume 19, pages 278-284 of Radiation Laboratories Series (McGraw-Hill, 1949). Delay control transistor 52 is normally non-conducting, is connected in parallel with base bias resistor 60 and has its base 66 connected to the D.C. output of a test signal generator 20 through line 25.

Prior to initiation of the resetting cycle, with transistor 51 not conducting and transistor 50 conducting, the charge on capacitor 53 is negligible and potential at the output 36 is slightly below ground potential. When transistor 50 is cut-off by the output of flip-flop 30, transistor 51 conducts and capacitor 53 begins to charge negatively through resistor 60 and base 55 of amplifier 51. The potential at 36 goes sufficiently negative to cause trigger amplifier 37 to operate. The time between the occurrence of the pulse from flip-flop 30 until trigger amplifier 37 operates is determined by the RC time constant of the charging network which is essentially controlled by the gain of amplifier 51. The time in this instance is approximately one minute.

When caused to conduct by test generator 20, transistor 52 operates to shorten the charging time of capacitor 53 by short-circuiting base resistor 60.

Reset action of the alarmed intrusion detection system is initiated by actuating test button 31 which triggers bi-stable flip-flop 30 and applies a positive potential to base 49 of normally conducting transistor 50 which is saturated during stand-by operation. This reverse biases and cuts off transistor 50 causing the potential on collector 56 of transistor amplifier 51 to fall toward the negative supply potential $-V$, i.e., in the direction to turn amplifier 51 on hard. The action of capacitor 53 causes amplifier 51 to conduct at a linear rate and capacitor 53 to charge through base bias resistor 60 at a linear rate. During this charging phase, delay control transistor 52 is reverse biased and is non-conducting.

When the charge across capacitor 53 reaches a predetermined level, $-V$, trigger amplifier 37 is forward biased and conducts. The output of amplifier 37 energizes coil 40 of reset relay 39 to close its contacts and connect source 43 to generator 20 and to alarm relay 11 through lines 45 and 44, respectively. Since test generator 20 was not triggered at the start of this reset cycle, the output of relay 39 has no effect on it. The effect on alarm relay 11 is to energize it and thus de-activate and reset alarm 12. Operation of alarm relay 11 also causes a unidirectional voltage to be applied via line 47 to flip-flop 30 to reset it. Until flip-flop 30 is thus reset, push button 31 has no effect on it.

Resetting of flip-flop 30 causes transistor 50 to again conduct and saturate. The potential on collector 56 of amplifier 51 becomes less negative and causes the latter to cut-off. Capacitor 53 discharges rapidly through transistor 50, and the output at line 36 becomes less negative until trigger amplifier 37 is cut-off. This de-energizes reset relay 39 and the resetting cycle is complete. Alarm relay 11 has a typical hold-in coil arrangement so that it remains energized after the input to it on line 44 is removed.

In order to test system operation, test button 21 of test generator 20 is depressed. This sends a simulated intruder signal to receiver 4 via line 22, and causes alarm device 12 to be activated if the intervening circuits are functioning properly. The outputs from discriminator circuits 6 and 6' are also applied via lines 27 and 27', respectively, to AND gate 26 to condition the latter for enabling resetting action. If either circuit 6 or 6' is not functioning properly AND gate 26 will prevent reset action taking place.

Another output from generator 20 is a negative pulse fed through line 25 to forward bias base 66 of delay control transistor 52. This transistor is maintained non-conducting, however, due to the reverse bias potential between its collector 67 and emitter 68.

A third output from test generator 20 is fed through line 23 to AND gate 26. When a trigger pulse from generator 20 and both discriminator circuits 6 and 6' are received simultaneously, AND gate 26 triggers bi-stable flip-flop 30 and initiates a cycle similar to the reset cycle described above. Briefly, the flip-flop 30 applies a positive potential to base 49 of transistor 50, causing it to cut-off. Amplifier 51 tries to turn on hard as the potential on collector 56 falls toward the negative supply potential. Due to the action of capacitor 53, the potential on base 55 of transistor 51 becomes negative and forward biases collector 67 of delay control transistor so the latter now conducts. Delay control transistor 52 saturates and essentially short-circuits base bias resistor 60, removing it from the circuit. When capacitor 53 charges to a predetermined voltage trigger amplifier 37 conducts and produces an output on line 38.

Assuming that the potential on line 36, at which trigger amplifier 37 fires, i.e., the potential to which capacitor 53 charges is much less than the supply voltage $-V$, the rate at which capacitor 53 charges is approximately

$$\frac{-V}{R_L(1+A)C_{fb} + C_{be}} \quad (1)$$

where

R_L is the amplifier load resistance 62,
 C_{fb} is the capacitance of capacitor 53,
 A is the effective gain of amplifier 51,
 C_{be} is the stray capacitance between the base and emitter of amplifier 51, and
 $-V$ is the negative supply potential.

When the current gain β , i.e., the rate of change of collector current to base current for a constant collector 40 to emitter voltage, of amplifier 51 is greater than the ratio of base bias resistance 60 to emitter bias resistance 61, the effective gain A of amplifier 51 is approximately equal to this ratio. Thus, a decrease in base bias resistance 60, due to conduction of delay control transistor 52, causes the effective gain of amplifier 51 to decrease and capacitor 53 to charge much more rapidly than during the reset cycle previously described. The difference in charge time of capacitor 53 during reset and system test preferably is approximately 50 seconds.

The output of trigger amplifier 37 energizes reset relay 39 which produces an output on line 45 to test generator 20 whose output at line 25 is thereby switched from negative to positive. This reverse biases delay control transistor 52 to cut it off. Reset relay 39 also resets alarm relay 11 in the same manner as described above in connection with the system resetting operation.

What is claimed is:

1. Intrusion alarm apparatus comprising microwave receiver means responsive to an intruder signal for producing an output, an alarm relay having first and second operating states, said relay being responsive to the output of the receiver means to change from the first to the second state, an alarm device connected to said relay to give an alarm when the relay is in said second state; and a system test circuit comprising a test generator for producing a simulated intruder signal and having first, second and third outputs, the first output of said generator being connected to said receiver means for actuating said alarm relay and said alarm device, an AND gate having a first input connected to the output of the receiver means and a second input connected to the second output of said generator,

a bi-stable flip-flop connected to the output of said AND gate and having first and second operating states,
 said flip-flop being responsive to the output of the AND gate to change from the first to the second operating state,
 a delay network having a first input connected to the output of said flip-flop and a second input connected to the third output of the test generator,
 said network being responsive to the output of said generator and to the output of said flip-flop in its second operating state for producing an output after a predetermined time delay,
 said alarm relay being responsive to the output of said delay network for changing from said second to said first operating state to de-activate said alarm device,
 and means for resetting said flip-flop to its first operating state in response to change of the alarm relay to its first operating state. 20

2. Apparatus according to claim 1 in which said delay network comprises first and second transistors having collectors connected to the network output,
 said first transistor having its base connected to the output of said flip-flop, a capacitor connected between the collector and base of said second transistor, a resistor connected between the base and emitter of said second transistor,
 and means responsive to said third output of the generator for selectively shorting out said resistor whereby to shorten the charging time of said capacitor. 25

3. In combination,
 intrusion alarm apparatus responsive to condition for giving an alarm,
 a test and reset circuit comprising a test generator having first, second and third outputs,
 means to actuate said generator to generate signals at said three outputs, 30
 the first output being connected to said apparatus to simulate the condition and give the alarm,
 an AND gate having an output and having a first input connected to an output of said apparatus and a second input connected to the second output of the generator,
 a bi-stable flip-flop having an input connected to the output of said AND gate and having an output, 40
 and a delay network having a first input connected to the output of said flip-flop and a second input connected to the third output of said generator,
 said network having an output connected to said apparatus for resetting same a predetermined time after said test generator is actuated,
 and means connecting said flip-flop to said apparatus for resetting the flip-flop simultaneously with the alarm apparatus. 50

4. Intrusion alarm apparatus comprising
 microwave receiver means responsive to an intruder signal for producing an output,
 an alarm relay having first and second operating states, 60
 said relay being responsive to the output of the receiver means to change from the first to the second state,
 an alarm device connected to said relay to give an alarm when the relay is in said second state; and a system test circuit comprising a test generator for producing a simulated intruder signal and having first and second outputs,
 the first output of said generator being connected to 65
 said receiver means for actuating said alarm relay and said alarm device,
 an AND gate having a first input connected to the output of the receiver means and a second input connected to the second output of said generator, 70

a bi-stable circuit connected to the output of said AND gate and having first and second operating states, said bi-stable circuit responsive to the output of the AND gate to change from the first to the second operating state,
 a delay network having input connected to the output of said bi-stable circuit,
 said network being responsive to the output of said bi-stable circuit when in the second operating state for producing an output after a predetermined time delay, said alarm relay being responsive to the output of said delay network for changing from said second to said first operating state to de-activate said alarm device,

and means for resetting said bi-stable circuit to its first operating state in response to change of the alarm relay to its first operating state.

5. Intrusion alarm apparatus comprising
 receiver means responsive to an intruder signal for producing an output,
 an alarm relay having first and second operating states, said relay being responsive to the output of the receiver means to change from the first to the second state,
 an alarm device connected to said relay to give an alarm when the relay is in said second state; and a system test and reset circuit comprising a test generator for producing a simulated intruder signal and having first, second and third outputs, 30
 the first output of said generator being connected to said receiver means for actuating said alarm relay and said alarm device,
 an AND gate having a first input connected to the output of the receiver means and a second input connected to the second output of said generator,
 a bi-stable flip-flop connected to the output of said AND gate,
 said flip-flop being responsive to the output of the AND gate to produce an output, 40
 manual reset means connected to said flip-flop and operative independently to produce an output from the flip-flop,

a time delay network having input connected to the output of said flip-flop and another input connected to the third output of the test generator,
 said network being responsive to the output of said generator and to the output of said flip-flop for producing an output after a first time delay and being responsive to the output only of said flip-flop for producing an output from the network after a second time delay greater than the first delay,
 said alarm relay being responsive to the output of said delay network for changing from said second to said first operating state to de-activate said alarm device,

and means for resetting said flip-flop in response to change of the alarm relay to its first operating state.

6. Intrusion alarm apparatus comprising
 microwave receiver means responsive to an intruder signal for producing an output,
 an alarm relay having first and second operating states, said relay being responsive to the output of the receiver means to change from the first to the second state,
 an alarm device connected to said relay to give an alarm when the relay is in said second state; and a system reset circuit comprising a bi-stable flip-flop having first and second operating states, manual means associated with said flip-flop and operative to change same from the first to the second operating state,
 a delay network having input connected to the output of said flip-flop,
 said network being responsive to the output of said

flip-flop when in the second operating state for producing an output after a predetermined time delay, said alarm relay being responsive to the output of said delay network for changing from said second to said first operating state to de-activate said alarm device,

and means for resetting said flip-flop to its first operating state in response to change of the alarm relay to its first operating state.

7. Intrusion alarm apparatus responsive to a condition for giving an alarm, 10
 a test signal generator having first and second outputs, means for selectively actuating said generator to produce signals at said outputs, and circuit means for resetting said apparatus,
 15 said circuit means having an output connected to said apparatus and having a first input connected to the second output of said generator and a second input connected to said apparatus,
 said apparatus being responsive to a signal on the first output of said generator to give an alarm,

said circuit means being responsive to the signal on the second output of the generator and the alarming of the apparatus to produce a signal output for resetting said apparatus.

- 5 8. Apparatus according to claim 7 in which said circuit means has actuator means for selectively actuating said circuit means independently of said generator to produce a signal on the output of said circuit means for resetting said apparatus.
